UNITED STATES PATENT OFFICE.

VANCE W. PEEL, OF TOPEKA, KANSAS.

COMBINED LATCH AND HANDLE.

1,015,338.

Specification of Letters Patent. Patented Jan. 23, 1912.

Application filed March 10, 1911. Serial No. 613,592.

To all whom it may concern:

Be it known that I, VANCE W. PEEL, citizen of the United States, residing at Topeka, in the county of Shawnee and State of Kansas, have invented certain new and useful Improvements in Combined Latches and Handles, of which the following is a specification.

This invention comprehends certain new and useful improvements in combined latches and handles for doors of any character, and the invention has for its primary object an improved device of this character which will be simple in construction and efficient in operation, the parts being few in number and capable of being easily manufactured.

With this and other objects in view, as will more fully appear as the description proceeds, the invention consists of certain constructions, arrangements and combinations of the parts that I shall hereinafter fully describe and claim.

For a full understanding of the invention, reference is to be had to the following description and accompanying drawing, in which:

Figure 1 is a perspective view of a combined latch and handle embodying the improvements of my invention; Fig. 2 is a sectional view on the line $x-x$ of Fig. 1; Fig. 3 is a rear view; Fig. 4 is a detail perspective view of the locking pin; and, Fig. 5 is a fragmentary perspective of the latch stem.

Corresponding and like parts are referred to in the following description and indicated in all the views of the accompanying drawing by the same reference characters.

Referring to the drawing, the numeral 1 designates a door which in the present instance is a swinging door, but which may be a sliding door instead, and 2 designates the door frame. A casing 3 is secured in any desired way to the face of the door 1, and a latch stem 4 is mounted for a turning and longitudinally reciprocating movement in said casing, the latch being provided with a loop handle 5 by which it may be manipulated.

A keeper bracket 6 is secured to one side of the door frame 2 and a locking pin 7 is mounted for vertical movement in said bracket, the lower end of the pin being designed to enter a recess 8 in one end of the latch stem 4 so as to engage the shoulder

formed by one end of the recess to hold the latch in locked position. Preferably the lower end of the locking pin 7 is beveled as indicated at 9, whereby it will ride over the adjoining end of the latch stem 4 as the latter is moved to locking position.

In order to prevent the locking pin from being jarred from its place and lost, as for instance when the device is applied to a car door, the pin is connected to the bracket 6 for a limited movement therein by being formed with a slot 10 receiving a pin 11. The locking pin 7 is also formed with a transverse slot 12 communicating with a transverse slot 13 in the bracket, whereby a seal of any character may be passed through these transverse slots and hold the pin 7 in locked position. The latch stem 4 is formed intermediate of its ends with a perforation 14, which may also accommodate a seal or a padlock as in the present instance, to prevent the retraction of the latch independently of the locking pin 7.

In those cases where it is desired that the door be susceptible of unlatching from both faces, the stem 4 is provided with a perpendicularly projecting actuating rod 15 secured thereto in any desired way and adapted to work in an angular slot 16 formed in the door 1.

It is to be understood that my improved combined handle and latch is applicable for use with car doors, either swinging or sliding, for the doors of rooms of residences or the like, and in fact is generally applicable for all the purposes for which a device of this character is designed.

From the foregoing description in connection with the accompanying drawing, the operation of my improved latch and handle will be apparent. In the practical use of the device, it is only necessary to grasp the handle 5 to close the door and to simultaneously move the latch stem 4 into the bracket 6. The handle 5 will, of course, in this operation, be held in substantially perpendicular relation to the adjoining face of the door, particularly if the rod 15 be connected to the stem 4, as before specified. As soon as the door has been closed, and the stem 4 moved into the bracket 6 and the handle 5 released, the weight of the handle will cause the stem 4 to turn about its longitudinal axis, so as to bring about the proper registry between the notch or recess 8 of the stem and the locking pin 7, whereby the

pin will engage the stem to lock the door in closed position, this locking movement being also participated in by the entering of the rod 15 into the vertically projecting portion of the angular slot 16 that is formed in the door 1. It will be understood, by reference to the drawing, that the actuating rod 15 not only serves as a handle to manipulate the latch from that side of the door which is opposite the handle 5, but that said rod 15, in the retracted position of the stem 4 will hold the handle 5 out from the door whereby it may be easily grasped, owing to the fact that the pin 15 will then be lodged in the horizontal portion of the slot 16.

Preferably, the casing 3 is made in two separate or independent sections designated A and B respectively. By this construction and arrangement of parts, my improved combined latch and handle is equally applicable to sliding or rolling and hinged doors. When the device is applied to a hinged door, as in the present instance, the section A is slid back to abut against the section B as illustrated in Fig. 1, thereby permitting the latch stem to be retracted preparatory to swinging the door open. But when the device is intended for use with a sliding or rolling door, it is to be understood that the section A is slid forwardly away from the section B and is secured to the door a distance from the section B sufficient to prevent any longitudinal movement of the latch stem, the latch stem being, with this arrangement of parts permitted to have no longitudinal movement whatever, none being necessary with a rolling or sliding door.

What I claim is:

40. 1. A device of the character described, comprising a casing, a latch stem mounted for a turning and longitudinal movement therein, a handle connected to said stem, a keeper bracket, and a locking pin mounted in said bracket for a limited longitudinal movement therein, the latch stem being provided at one end with a shoulder for engage-

ment by the adjoining end of the locking pin.

2. A device of the character described, 50 comprising a casing, a latch stem movable longitudinally and rotatably in the casing, a handle connected to said stem, the stem being formed at its free end with a shoulder, a keeper bracket into which said end 55 of the stem is adapted to project, and a locking pin mounted for a limited longitudinal movement in said bracket and designed for locking engagement with the shoulder of the latch stem, the bracket and locking 60 pin being formed with registering transverse slots designed for the reception of a seal, as and for the purpose set forth.

3. A device of the character described, 65 comprising a casing constructed in two separate and disconnected parts each of which is arranged for separate attachment to a door, a latch-stem mounted for free movement in said casing, a loop handle connected at its ends to said stem, a keeper bracket, 70 and a locking-pin mounted in said bracket for a limited longitudinal movement therein, the latch-stem being provided at one end with a shoulder for engagement by the adjoining end of the locking-pin, the combined width of the two parts of the casing 75 being less than the distance between the two ends of the handle, whereby the two parts of the casing may be secured to a support in abutting relation with each other so as 80 to permit the stem to have both a turning and a longitudinal movement, and whereby, the two parts may be separated and secured to a support in spaced relation to each other and in engagement with the end of the han- 85 dle, respectively, so as to limit the movement of the latch-stem to a turning movement.

In testimony whereof, I affix my signature in presence of two witnesses.
